UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,202,867.

Specification of Letters Patent. Patented Oct. 31, 1916.

Application filed March 17, 1913. Serial No. 754,862.

To all whom it may concern:

Be it known that I, HAAKON A. MARTIN, a citizen of the United States, residing at Dayton, in the county of Montgomery and

5 State of Ohio, have invented certain new and useful Improvements in Cash-Registers, of which I declare the following to be a full, clear, and exact description.

This invention relates to improvements in 10 accounting mechanisms such as cash registers, and has more particular relation to a mechanism for differentially setting the actuating members of the accounting device.

The principal object of the invention is to 15 provide novel means for positioning the actuating members of the accounting device, whereby the amount of each successive transaction can be added to the previous total of preceding transactions.

20 Another object of this invention is to provide a manipulative means whereby a detent plate may be moved in either direction, and the depressed key thereby released.

A further object is to provide a mechanism 25 which is effective upon the operation of the machine whereby a detent plate can be moved in either direction and thereby release the keys which have been operated.

With these and incidental objects in view, 30 the invention consists in certain novel features of construction and combinations of parts, the essential elements of which are set forth in appended claims, and a preferred form of embodiment of which is hereinafter 35 described with reference to the drawings which accompany and form part of the specification.

Of said drawings: Figure 1 is a transverse sectional view of the machine embodying the present invention. Fig. 2 is a detail of a cam employed to rock the totalizer into engagement with its actuating rack. Fig. 3 is a detail of a cam employed to restore the transfer mechanism to normal position.

45 Fig. 4 is a detail section taken along a bank of keys and showing the transfer mechanism. Fig. 5 is an enlarged detail of the transfer pawls. Fig. 6 is a detail of a cam employed to actuate the key releasing arm.

50 Fig. 7 is a detail section taken through a bank of keys showing the mechanism for differentially positioning the actuating rack of the totalizer. Figs. 8 and 9 are details of the cams employed to rock certain actuating 55 jaws and to close the jaws respectively. Fig.

10 is a detailed front view of the lower portions of the determining members showing the rollers which are adapted to be gripped by the operating jaws.

This invention has more particularly to 60 do with a novel differential mechanism whereby movement of a main operating device, constant in extent, may give a differential movement to the actuating devices for the totalizer and indicating mechanisms. 65 The differential movement is determined by differentially moving an element connected to the member carrying the actuating rack for the totalizer in the path of jaws moved by the main operating mechanism.

In particular the invention provides for 70 two irregularly shaped members for each bank of keys. The upper amount keys in the bank engage one of these members and thereby rock the member differentially about 75 a pivotal point. The keys in the lower portion of the bank engage in a like manner with the other member. One of the members carries a pin which operates in a slot in a link. This link is secured to an arm by a 80 pin and this arm has a fixed pivot, while the pin also serves as a pivotal center for the other member. When a key is depressed a

85 pair of jaws grip a roller on the member which has been moved, and when the jaws are given a movement by the main operating mechanism, the element carrying an actuating rack is moved differentially. When the rack has been given this differential setting, the totalizer is rocked into engagement with 90 it, and as the rack is restored to its normal position the amount of the transaction registered is added on the totalizer. Each bank 95 of keys is provided with a detent which is moved upward if a lower amount key is depressed, and in the opposite direction when an upper amount key is depressed. An upper and a lower key cannot therefore be depressed at the same time. A release key is also provided which, when it is depressed, 100 gives the detent a further movement in the direction in which it is already moved whereby the depressed key is released. At the end of the operation of the machine a device controlled by the main operating mechanism releases the keys automatically by raising or lowering the detent plate.

105 Referring to the drawings, 1 to 9 are the amount keys, and 10 is the release key. The numbers 1 to 9, designating these keys, will 110

be taken for the sake of illustration, as also representing the value of the respectively designated keys. A detent plate 11 is slidably mounted on the frame of the machine 5 by pins 13 fast to the frame, engaging in the slots 12 in the detent plate. The keys 1, 2, 3, and 4 each carry a roller 16 which, when any of these keys are depressed, engages with the inclined face of a recess in the detent plate 11 whereby the detent is lowered. Keys 5, 6, 7, 8, and 9, or the lower 10 five keys in each bank, are each provided with a roller 17 which when any one of these keys is depressed, engages with its respective inclined face of its respective recess in the detent plate 11 whereby, because of the construction of the inclined face, the detent plate 11 is raised. The detent plate 11 is held in its normal position when the keys 15 are released, by pawls 19 and 20 (Fig. 4). These pawls are loosely mounted on a rod 22 and each engages a pin 23 projecting from the detent plate 11. Extending rearwardly from each of these pawls is a curved 20 arm 24, which is normally in contact with a fixed pin 25 extending from the frame of the machine. A spring 26, which is constantly under tension, connects the rear ends 25 of these rear arms of the pawls 19 and 20. When the detent plate 11 is in its normal 30 position both of these pawls engage the pin. When the detent plate is moved down and the depressed key is released the pawl 20 brings the detent plate again into its normal 35 position, but when it is raised and the depressed key then released, the other pawl brings the detent plate 11 back to its normal position. A manipulative device is provided, whereby the amount key, which has 40 been operated, can be released. The detent plate has a projection 27 with two beveled faces. A pin 28 projects from the release key 10. When the detent plate 11 is lowered, as has been explained, if the release 45 key 10 is depressed the pin 28 will engage the upper beveled face of this projection 27 giving the detent plate 11 a slightly further downward movement, whereby the depressed amount key is released. The detent 50 plate is then returned to its normal position by the pawl 20. When the detent plate is raised the roller 28 engages the lower beveled face of this projection 27 and in the same manner detent plate 11 is restored to 55 its normal position. A means is also provided whereby the amount keys are released upon the operation of the machine. An arm 31 is loosely mounted upon a shaft 29 and carries at its upper end a projection which 60 has two beveled faces. Extending downwardly from this arm is another arm 32 to which at its lower end is secured a pitman 33. This pitman at its rear end is forked and straddles a main drive shaft 34, and 65 also carries a roller 35 which engages in the race of a disk 36 (Fig. 6). The detent plate 11 at its lower end has a projection 30 with beveled faces. The race of the disk 36 is so constructed that toward the very end of each operation of the machine the pitman 70 is given a slight rearward movement, whereby the arm 31 is oscillated in a clockwise direction. When the detent plate 11 has been moved down by one of the upper amount keys and the machine has been operated, the lower beveled face of the projection on the arm 31 engages the upper beveled face of the projection 30 on the detent 75 plate 11, whereby the detent is given a slightly further downward movement and the key which has been pressed is released. When the detent plate has been raised the upper beveled face of the projection of the arm 31 engages with the lower beveled face of the projection 30 of the detent and the 80 depressed key is released, as in the other operation. 85 One of the novel features of the machine is a means for differentially positioning a member carrying an actuating rack, whereby the totalizer is to be actuated. An irregularly shaped member 37 (Fig. 7), is pivoted at its upper end to a link 39 by a pin 41 extending from the arm engaging in a slot 42 in the link. Another irregularly formed 90 member 38 is pivoted to the lower end of this link 39 by a pin 45. This link is pivoted to an arm 46 by the same pin 45. The arm 46 is rigidly secured to an arm 47, which in turn, is loosely mounted on a shaft 48. At its inner end the arm is secured to a link 49, the other end of the link being pivoted to a plate 52 which is capable of being given a reciprocating movement through the pins 43 carried by the machine frame extending through slots 44 in the plate. The members 37 and 38 are held in normal position by the springs 37^a and 38^a respectively and at their lower ends each member is provided with a roller 53 (Fig. 10). The member 37 is so constructed that when any of the first four amount keys in the corresponding bank is depressed the roller on the key engages with this member and rocks it about its pivot 41. The extent of movement is determined by the value of the amount key, and is inversely proportional to the value represented by the key. For example, if the key representing one cent is depressed the member 37 is given four units 100 of movement about its pivot 41 whereas if the key representing four cents is operated the member 37 is given but one unit of movement. The other member 38 is rocked about its pivot 45 by the five lower amount keys in each bank, and its movement is also determined by the value of each of these keys. The key in this series which represents the least value gives the member 38 105 the greatest extent of movement, namely 110 115 120 125 130

five units while the key of greatest value moves the member 38 but one unit. As the value of the key determines its relative position in the banks it may be said that the 5 extent of movement of either of these members depends upon the relative position of the depressed key in either series of each bank of keys.

The members 37 and 38 just described are 10 given a translatory movement through a pair of jaws, which in turn are rocked about their pivotal centers by the main operating mechanism. One jaw 55 is pivoted to the other jaw 58 by a pin 59, while the jaw 58 is rigidly mounted upon a shaft 61. The 15 jaw 55 carries a plate 54, the inner edge of which has four notches, and the lower jaw 58 has a corresponding plate 56. These plates are so constructed that when the member 37 is rocked about its pivot and the jaws are then closed, they grip the roller 53 on the end of the member in its set position. If the "1" key has been depressed, this roller 20 will be in a position where the first notches from the pivot pin 59 of the jaws will grip it. If the "4" key has been depressed the roller will be held in the outside notches. The jaw 55 is also provided with a plate 57 which is parallel to the plate 54. This plate 25 54 at its lower edge has five notches and the lower jaw has a corresponding plate with five notches. These plates are so constructed as to grip the roller 53 on the arm 38 when it has been rocked about its pivot by 30 any one of the five lower keys in the bank. These jaws are operated by the main operating mechanism. The jaw 55 at its lower end has an arm 60 with a cam face 610. A roller or pin 62, which projects from an arm 35 63 mounted on a hub of a shaft 64, engages with this cam face 610, (Fig. 6). Fast to this same hub is an arm 65 to which is pivoted a pitman 66, (Fig. 1). The pitman at its rear end is bifurcated and straddles the 40 shaft 34 and near the same end carries a projecting roller 67 which engages in the cam groove of a disk 68, (Fig. 9). This cam groove is so constructed that at the very beginning of the operation of the machine the pitman 66 is given a rearward movement 45 whereby the arm 63 is rocked in a counter-clockwise direction. This movement of the arm, through the engagement of the roller 62 with the cam face 610 lowers the jaw 55 50 thereby gripping one of the rollers 53. The jaws in their closed position are then given an oscillatory movement by the following described mechanism.

Fast on the shaft 61 is an arm 69, which at 55 its outer end, is pinned to a pitman 71, which at its rear end is slotted and straddles the drive shaft 34 and also carries a roller 72 which engages in the cam groove of a disk 73 (Fig. 8). This cam groove is so 60 signed that when the disk begins to rotate

the pitman 71 is given a short rearward movement, whereby the lower jaw 58 is raised slightly and hence brought into contact with one of the rollers 53. Upon further rotation of the disk the pitman 71 is 65 given a further rearward movement, which, as can be readily seen, will rock the jaws in their closed condition about the pivot 64, the extent of movement being, of course, always the same. Because these jaws grip one of the rollers 53 the member to which the roller gripped is secured, is moved in the direction of its length. The extent of movement of either arm 37 or 38 depends upon the differential setting of its respective rollers 53. If 70 the roller 53 is near the pivotal point 59 of the jaws the members 37 or 38 will not be given as great an extent of movement as if the roller was near the outer end of the jaws. In other words the extent of trans- 75 latory movement of these members is now inversely proportional to the extent of movement of the members 37 and 38 about their pivots. For example if the five cent key is depressed the member 38 will be given 80 five units of movement about its pivot. Now when its roller is engaged by the jaws and the jaws given an oscillatory movement, the member 38 will receive one unit of movement in the direction of its length. If the nine cent 85 key is operated the member 38 will first be given one unit of movement about its pivotal center and then five units of movement in the direction of its length. When any of the first 90 four amount keys in each bank of keys is 95 pressed, the arm 37 as has been said, will be raised by the rocking of the jaws. This arm however, is raised a distance equal to the length of the slot 42 before the link 39 is raised. When the roller on the member 38 100 is gripped by the jaws and the member 38 moved upward, the plate 52 is moved a corresponding distance. This idle movement of the member 37 is provided because the member 38 moves the plate 52 differentially 105 from five to nine spaces without any idle movement. A distance equal to five units must then be traveled over by the member 37 before the plate is moved in order that the member 37 may differentially move the plate 110 from one to four spaces.

By the construction just explained, a movement of one to nine steps can be given to this plate 52 by the same extent of movement being given each time to the jaws 55 and 58. This construction rather than one employing but one irregular member to be differentially positioned, has been used as it can readily be seen that it is preferable to provide shorter jaws and at the same time 120 obtain the desired extent of movement of the plate 52. By the devices which have been clearly described, plate 52 is differentially moved by the rocking of the jaws which 125 grip the determining members 37 or 38 after 130

they have been differentially positioned under the operation of the amount keys.

The totalizer and its actuating device may be next described. Each plate 52 carries an actuating rack 75, provided with teeth 74 which add the amount of the transaction upon the totalizer 78 when the totalizer has been rocked into mesh with the actuating rack, as the rack is being restored to its normal position. The totalizer elements are rocked into engagement with the rack 75 at the proper time by the following described device. The totalizer elements are loosely mounted on a shaft 79, which is carried by an arm 81 loose on a shaft 82. This arm has a curved slot 85^a into which projects a pin 83 fast on an arm 84 which is rigidly mounted on a sleeve surrounding a shaft 70. Fast to this same sleeve is an arm 85 which at its rear end is secured to a pitman 86. The rear end of the pitman straddles the main drive shaft 34 and has a roller 89 engaging in the race 88 of the box cam 87 as shown in Fig. 2. This race is so constructed as to rock the arm 81 downward and thereby rock the totalizer into engagement with the actuating racks 75 when these actuating racks have been differentially positioned. Now when these racks are given their return movement to normal position the amount of the transaction registered will be added on the totalizer.

The transfer mechanism for the totalizer is shown in Fig. 4. Arms 91 are pivoted to the plate 52 by the pins 93. Connecting the other ends of these arms is a link 94. The upper arm 91 is normally held in engagement with a pin 95 fast on the plate 52 by a spring 96, which is constantly under tension and extends from the plate 52 to the arm 91. The rack 75 carries a lug 106, and the plate 52 carries a lug 108. A rod 107 is fast to the lug 106 and engages in a slot in the lug 108. A spring surrounds this rod 107 and being continually under a tension tends to lower the rack 75, the rack 75 being slidably mounted upon the plate 52 by the pins 76, projecting from the plate 52, engaging in the slots 77 in the rack. The rack 75 has an extension 104 in which is a recess 103. In this recess a projection 102 on one arm of a bell crank 99, pivoted to the plate 52 by the pin 101, engages. The other arm of this bell crank carries a roller 98 which is in engagement with an inclined face of the projection 97 of the link 94. The transfer tripping pawls are shown in Fig. 5. These pawls are mounted on a hub 111 surrounding the shaft 100. This hub has a small opening into which the end of a spring 119 engages. The pawl 110 has a projecting rod 110^a which is held in contact with the link 94 adjacent to the totalizer element of the next higher denomination by the spring 119. Each totalizer element carries a projection

or pin 112 which, when a transfer is to be accomplished, engages the pawl 109 whereby it and the pawl 110 are rocked. The rocking of these pawls forces the projection 102 of the bell crank out of engagement with the recess 103 in the projection in the rack 75 by the engagement of the inclined face of the projection 97 on the link 94 with the roller 98 on the other arm of the bell crank 99. When this disengagement is accomplished the rack 75 is given an additional movement of one unit by the spring surrounding the rod 107, whereby the totalizer element is moved one step.

At the very end of the operation of the machine this rack is restored to its normal position. The rack at its lower end and on the same side as is the teeth has a projection 118 with which a projection 117 on an arm 116 fast to the shaft 118^a may engage. A downwardly projecting arm 116^a is rigidly mounted on the shaft 118^a and has secured at its lower end a pitman 115 which at its rear end straddles the drive shaft 34. This pitman 115 carries a roller 114 which engages in the cam groove of the box cam 113 (Fig. 3). This cam is so constructed that at the very end of the operation of the machine the pitman 115 is given a short forward movement, whereby the bell crank 116 is rocked about its pivot and the projection on the arm 117 engages with the projection 118 thereby moving the rack 75 upward. The projection 102 on the one arm of the bell crank 99 then engages the recess 103 in the projection on the rack 75, because the inclined face of the projection 97 on the rack 75 has been taken out of engagement with the roller 98 and the spring 105 brings this projection 102 into engagement with the recess 103 as soon as the recess presents itself. The transfer operation therefore is as follows: Upon the operation of the machine the plate 52 is raised and when the plate is returned from its set position to its normal position the amount of the transaction is added on the totalizer 78, the totalizer being rocked into engagement with the rack 75 during this return movement of the plate 52. When a transfer is to be accomplished the transfer pawls are moved as explained. The projection 102 on the one arm of the bell crank 99 is taken out of engagement with the recess 103 in the projection 104 on the rack 75 and the rack is given one unit of movement under spring 120 action. Toward the very end of the operation of the machine the bell crank 116 is rocked in a counter-clockwise direction whereby the rack 75 is returned to its normal position and the projection 102 of the bell crank 99 again engages the recess 103 in the rack and holds it in normal position until the next operation of the machine.

The indicator mechanism is shown in Fig. 1. The members which determine the dif-

ferential movements of the actuating racks for the indicators are connected to the differentially positioned plates 52. Further operation of the machine then actuates segmental racks, which gear with the pinions secured to the indicators and thereby set up the amount on the indicators. The element which determines this differential movement of each actuating rack consists of a segment 126, having notches 127 on its periphery, and also an arm 129 with a circular recess 130 into which a roller 131 on the differentially positioned plate 52 engages. When the plate 52 is moved, as has been explained, the engagement of the roller with the slot 130 of the forked arm differentially positions this member. Alining pawls 132 are provided to engage in the notches of this segment 126 to hold it in position, while the actuating racks 142 give the indicators a rotary motion. These pawls 132 are loosely pivoted on a rod 133 and are in constant contact with short arms 125, rigidly mounted on a shaft 120. Fast to this same shaft is a rearwardly extending arm 134 which at its outer end, is secured to link 135, the lower end of this link being fastened to one of the arms 136 of a bell crank loosely mounted on a shaft 136^a. To the outer end of the other arm 137 of this bell crank is secured a pitman 138 which consists of a slotted plate straddling the shaft 34. At the forward end of this pitman is a roller 139 engaging in the cam groove of a disk 141, shown in full lines in Fig. 1. When the plate 52 is being differentially positioned the member 126 is differentially rocked about its pivotal point 124. The pitman 138 is then given a backward movement because of the construction of the cam groove in the disk 141 and the short arms 125 are rocked about the shaft 120 in a counter-clockwise direction thereby bringing a projection on the arm 132 into engagement with one of the notches of the segments 126. Each segment is held in this position until after the indicators 144 have been differentially set up. The actuating member for the indicator consists of a segmental rack 142 carrying teeth which engage with a pinion 143 rigidly secured to the indicator elements and at its lower end carries a pear shaped projection 146 with a pear shaped slot 146^a. This actuating member is loosely pivoted upon the shaft 124. A roller 147 operates in an elongated slot 128 in the segment 126, and also in the pear shaped slot 146^a of the pear shaped projection 146. This roller 147 extends from the upper end of a link 148, the lower end of which is secured to the arm 149 of a bell crank. The lower arm 151 of this bell crank is secured to a short pitman 152, which at its forward end straddles the shaft 34 and near its rear end carries a roller 153 which engages in the cam groove of a disk 141, shown by the

dotted lines in Fig. 1. This cam groove is so constructed that after the member 126 has been secured in its differential position, the pitman 152 is given a rearward movement whereby through the bell crank and the link 148 the roller 147 is lowered in the elongated slot 128. When the roller is lowered it engages with one of the inner walls of the pear shaped slot 146^a, and brings the lower end of this slot and the lower end of the elongated slot 128 into coincidence. This operation of the machine just described imparts to the actuating segment 142 the differential setting given to the segment 126. Toward the end of the operation of the machine the arms 125 are lowered and thereby the pawls 132 drop out of engagement with the notches in the segment 126. Then when the plate 52 returns to its normal position the segment 126 is also restored to its normal position, and the race shown by dotted lines on the disk 141 returns the pin 147 to its normal position. The actuating member for the indicator also carries a rearwardly extending arm 156. A link 157 connects the arm 156 to an arm 158 rigidly secured to a sleeve surrounding a shaft 159. To this same sleeve type carriers, (not shown), can be connected. Each of these actuating racks is secured to its corresponding type carrier by the means just described.

The operation of the machine described may be briefly recapitulated. When one of the four upper amount keys in each bank is depressed the irregularly shaped member 37, with which the roller 16 on the key depressed engages, is given an extent of movement corresponding to the value of the amount key. The crank handle, which is not shown in the drawings but may be geared to the shaft 34 in the usual manner is turned and the main drive shaft 34 rotated. The operation of the cam 68 then closes the jaws 55 and 58 and the cam 73, because of its construction, then rocks these jaws about their pivotal center 59. The upper end of the irregularly shaped member 37 has an idle movement before the plate 52 is raised because of the slot 42 in the end of the link 39. The plate 52, and therefore the rack 75 which it carries, are given as many units of movement as correspond to the value of the key depressed. When one of the lower keys is depressed the roller 53 on the irregularly shaped member 38 is gripped by the jaws 55 and 58 and as this member is pivoted to the arm 46 secured to the plate 52, by the link 49, there is no idle movement and the plate 52 is given a movement corresponding to the value of the amount key depressed. When this plate 52 has been differentially positioned the totalizer 78 is rocked into engagement with the actuating rack 75. The jaws 55 and 58 are then oscillated in the opposite direction whereby the differentially

positioned member 52 is restored to its normal position and thereby the amount of the transaction registered is added on the totalizer. If a transfer is to be accomplished during the operation of the machine, the actuating rack is given an extra unit of movement by the spring which surrounds the rod 107, this movement being made possible by the disengagement of the projection 102 on the one arm of the bell crank 99, from the recess 103 in the projection on the rack 75, as has been fully described. This rack is restored to its normal position at the end of the operation of the machine by the engagement of the projection 117 on the arm of the bell crank 116 with the projection 118 on the rack 75. When the plate 52 is raised the engagement of the pin 131 in the curved recess 130 of the arm 129 differentially positions the segment 126. The alining pawl 132 is then rocked into engagement with one of the notches 127 in the segment. Now when the link 148 is lowered, the roller 147 on its upper end engages with the inner face of the pear shaped slot 146^a of the actuating member for the indicator and imparts the differential setting of the member 126 to the indicator 144 by the engagement of the segment rack 142 with the pinion 143, which is rigidly secured to the indicator 144. The arm 31 is finally rocked about its pivotal center 29, and the engagement with one of the beveled faces of the projection 30 on the detent releases the key depressed, whereby the detent is restored to its normal position by either of the pawls 20 or 19 according to the direction of movement of the detents.

While the form of mechanism herein shown and described is admirably adapted to fulfil the objects primarily stated, it is to be understood that it is not intended to confine the invention to the one form of embodiment herein shown and described as it is susceptible of embodiment in various forms, all coming within the scope of the claims which follow.

What is claimed is—

1. In a machine of the class described the combination with a bank of keys; of a locking plate for said keys, constructed to be moved in one direction upon the operation of certain keys in the bank and in the opposite direction upon the operation of certain other keys in the bank; a release key in said bank; and a projection on said locking plate whereby said release key by its engagement with said projection releases the key depressed.

2. In a machine of the class described the combination with a bank of keys; of a locking member for said keys constructed to be moved in either direction dependent upon the key operated and having a projection with two beveled faces and a release key adapted to engage either of said beveled

faces of said projection when the key is operated, whereby the locking plate is given an additional extent of movement thereby releasing the key depressed.

3. In a machine of the class described, the combination with a bank of keys; of a locking member therefor, constructed to be moved in either direction dependent upon the key depressed; a projection on said member having two beveled faces; a cam arm and operating means for actuating the cam arm whereby the arm engages either face of the said projection and moves the locking member an additional step in the direction in which it has already been moved thereby releasing the key depressed.

4. In a machine of the class described, the combination with a bank of keys; of a slideable locking member therefor moved in either direction dependent on the key depressed, and having upper and lower projections each with two inclined faces; a manipulative device positioned to engage either face of said upper projection and give said locking member a further movement in the direction in which it has been moved thereby restoring the key depressed; a movable member positioned to engage either face of said lower projection and thereby give said locking member a further movement in the direction in which it has been moved thereby releasing the key depressed; and a main operating device having connections to actuate said movable member.

5. In a machine of the class described, the combination with a bank of keys; of pivoted members differentially positioned thereby; a totalizer; an actuating member therefor; a slidably mounted plate carrying said actuating member; connections between the pivoted members and the plate; a jaw having a fixed pivotal center; a second jaw pivoted on said first jaw; operating means for the second jaw, whereby the jaws are closed and the pivoted member, which has been differentially positioned, is engaged; and operative means for the first jaw, whereby the same is rocked about its pivotal center, thereby differentially positioning the plate.

6. In a machine of the class described, the combination with a totalizer; of an actuating member therefor; a plate carrying said member; a bank of keys; members differentially positioned by said keys; an arm having a fixed pivot; connections between said members and said arm, and said plate and said arm; a pivoted jaw; a second jaw; operative means whereby said jaws engage the member which has been differentially positioned; and operative means whereby said jaws are given a movement of invariable extent thereby differentially positioning the plate.

7. In a machine of the class described, the combination with an element to be differen-

tially positioned; of a bank of keys; two members differentially positioned by the keys; connections intermediate these two members, and these two members and the 5 element; and operative devices for moving either of the members differentially positioned whereby the differential setting of such member is imparted to the element.

8. In a machine of the class described, the 10 combination with an element to be differentially positioned; of two members having pivotal centers; connections intermediate said element and said members; manipulative means for differentially positioning said 15 members about their pivotal centers; and operative means for giving either member so positioned a variable movement in the direction of its length whereby the differential setting of said member is imparted to said 20 element.

9. In a machine of the class described, the combination with a bank of keys; of a totalizer; an actuating rack therefor; a plate carrying said rack; a determining element for 25 said plate, constructed to be differentially positioned by the keys of lower value; actuating means for said determining element; connections between the plate and the element whereby the said element is moved a 30 constant distance before the differential setting of the element is imparted to the plate; and another determining element differentially positioned by the other keys, said latter element being also moved by said actuating 35 means; and connections between said plate and said second element, whereby the plate is moved during this entire movement of the second element thereby imparting the differential setting of this element to the 40 plate.

10. In a machine of the class described, the combination with a totalizer; of an actuating rack therefor; a plate carrying said rack; a bank of keys; a pivoted determining 45 member which is differentially positioned by the keys and is so constructed that its extent of movement about its pivotal center is inversely proportional to the value represented by the key depressed; and operative devices constructed to engage the determining member in its differentially set position and impart to the same a translatory movement directly proportional to the value represented by the key depressed, whereby the 50 actuating rack is differentially positioned.

11. In a machine of the class described, the combination with an element to be differentially positioned; of a pivoted determining member; manipulative devices whereby said member is given an extent of movement about its pivotal center which is inversely proportional to the value represented by the device operated; operative means whereby said member is given a translatory movement 60 directly proportional to said value; and con-

nections between said member and said element whereby the latter movement of said member is imparted to said element.

12. In a machine of the class described, the combination with an element to be differentially positioned; of a determining member therefor; manipulative devices, whereby said member is given an extent of movement which is inversely proportional to the amount represented by the manipulative device operated; an operating means, whereby said member is positively given a second extent of movement which is directly proportional to said value and then positively returned to the position to which it was adjusted by operation of the manipulative device; and connections between said element and said member whereby said element has imparted to it the second movement of said member. 70 75 80 85

13. In a machine of the class described, the combination with a totalizer; of an actuating rack therefor; pivoted members for determining the differential movement of the totalizer; a bank of keys whereby said members are moved differentially about their pivotal centers; rollers on said members; an actuating device including two jaws each of which carry notched plates constructed to grip said rollers; operating means for closing and for moving said jaws in their closed condition, whereby the determining members are given translatory movements of variable extent. 90 95

14. In an accounting machine, the combination with an element to be differentially positioned; of two determining members therefor; a series of keys for differentially adjusting said members; and a device having an invariable extent of movement at each 100 operation of the machine and adapted to operate the members after they have been differentially adjusted whereby said element is differentially positioned. 105

15. In a machine of the class described, the combination with an element to be differentially positioned; of two irregularly shaped determining members therefor; a series of keys for differentially adjusting said members; and operating means for 110 moving the member which has been differentially adjusted to position the element differentially. 115

16. In a machine of the class described, the combination with an element to be differentially positioned; of two determining members for said element; a bank of keys for differentially adjusting said members; and operating means for moving the member which has been differentially adjusted 120 to position differentially the element. 125

17. In a machine of the class described, the combination with an element to be differentially positioned; of a determining member therefor; means for differentially 130

positioning said member; and a pair of operating jaws adapted to grip said member in its differentially set position and move the same in a constant direction differentially to position said element and then move the member in the reverse direction to the position to which it was adjusted by said means.

18. In a machine of the class described, 10 the combination with an element to be differentially positioned; of two determining members therefor; a series of keys for differentially adjusting either of said members; and operating mechanism for positively moving the member, which has been 15 differentially adjusted, first in a constant direction to position the element and then return the member to the position to which it was adjusted by the operated key.

19. In a machine of the class described 20 the combination with an element to be differentially positioned; of a determining member therefor capable of being given rotary and translatory movements of variable 25 extents; manipulative means for engaging said determining member and giving the same a rotary movement; and operating means for giving said member a reciprocating movement after the same has been given a rotary movement, whereby the said 30 element is differentially positioned.

20. In a machine of the class described the combination with an element to be differentially positioned; of a bank of keys; 35 two determining members for said differential element each being given rotary movements of variable extents by certain of said keys, the extent of movement being dependent on the key depressed; and operating 40 means for giving the moved member a reciprocating movement dependent upon the extent of the rotary movement whereby said element is differentially positioned.

21. In a machine of the class described 45 the combination with an element to be differentially positioned; of a determining member for said element; a series of keys adapted to engage the determining members and give the same rotary movements of variable extents; and operating means for giving 50 said member a reciprocating movement dependent upon the extent of the rotary movement whereby said element is differentially positioned.

22. In a machine of the class described 55 the combination with a bank of keys; of pivoted members differentially positioned thereby; an element to be differentially positioned; connections intermediate said members and said element; a pair of jaws having 60 a fixed pivotal center and adapted to engage the differentially moved pivoted member; and operating means for closing said jaws and oscillating the same about their pivotal center to engage the differentially moved

pivoted member and give the same a differential translatory movement whereby the element is differentially positioned.

23. In an accounting machine the combination with an element to be differentially positioned; of two determining members 65 therefor; a series of keys adapted to engage and differentially adjust said members; and a device having an invariable extent of movement at each operation of the machine and adapted to operate the members after 70 they have been differentially adjusted whereby said element is differentially positioned.

24. In a machine of the class described, the combination with a bank of keys; of a locking member for said keys constructed to be moved in either direction dependent upon the key operated and having a projection with two beveled faces; and means 80 adapted to engage either of said beveled faces of said projection for giving the locking plate an additional extent of movement thereby releasing the key depressed.

25. In a machine of the class described, 85 the combination with an element to be differentially positioned; of a determining member therefor; means for differentially positioning said member; and operating jaws adapted to grip said member in its differentially set position and move the 90 same to differentially position said element.

26. In a machine of the class described, the combination with a differentially positioned member; of operating jaws adapted 100 to grip said differentially positioned member and give the same a variable extent of movement dependent upon its differential position.

27. In a machine of the class described the combination with an element to be 105 differentially positioned; of determining means therefor; devices for differentially positioning said determining means; and operating jaws having opposing serrations and adapted to grip said determining means 110 in its differentially set position and move the same to differentially position said element.

28. In a machine of the class described, the combination with a member to be differentially positioned; of a determining element therefor; and pivoted operating jaws adapted to grip said element at varying 115 distances from the pivot of said jaws whereby oscillation of said jaws differentially positions said member.

29. In a machine of the class described the combination with a member to be differentially positioned; of a determining element therefor; and pivoted operating 120 jaws with opposing serrations and adapted to engage said element at varying distances from the pivot of the jaws whereby oscil- 125

lation of said jaws differentially positions said member.

30. In a machine of the class described, the combination with a member to be differentially positioned; of a plurality of determining elements therefor; and pivoted operating jaws adapted to grip one of said determining members at varying distances from the pivot of said jaws at an operation 10 of the machine whereby oscillation of said jaws differentially positions said member.

31. In a machine of the class described, the combination with an element to be differentially positioned; of a determining 15 member therefor; a bank of keys for engaging said member and moving it to an extent inversely proportional to the amount represented by the operated key; operating means whereby said member is given a second extent of movement which is directly proportional to said amount; and connections between said element and said member whereby said element has imparted to it the second movement of said member.

32. In a machine of the class described, the combination with an element to be differentially positioned; of a determining member therefor; manipulative means for adjusting the same; and operating means for positively rocking said member first in a constant direction, after it has been differentially adjusted by the manipulative means, to position differentially said element and then positively return the deter-

mining member to the position to which it 35 was adjusted by said manipulative means.

33. In a machine of the class described, the combination with an invariably moved driving mechanism, of an actuator having a normal starting point, a normally ineffective connection whereby the invariable movement of the driving mechanism may positively drive the actuator differential distances from its normal starting point and then positively return same to said starting point, and manipulative devices for differentially adjusting said connection to render same effective as a preliminary to an operation.

34. In a machine of the class described, the combination with an invariably moved driving mechanism, of an actuator having a normal starting point, a normally ineffective connection whereby the invariable movement of the driving mechanism may positively drive the actuator differential distances from its normal starting point and then positively return same to said point, and a series of keys selectively operable to effect differential adjustment of said connection to any one of its various positions as a preliminary to an operation.

In testimony whereof I affix my signature in the presence of two witnesses.
